METHOD AND APPARATUS FOR THERMO-CHEMICAL METAL SCARFING

William Allmang, Bloomfield, Carl E. Hartmann, Flora Park, and Ivan P. Thompson, Elizabeth, N. J., assignors to Union Carbide Corporation, a corporation of New York

Application May 26, 1953, Serial No. 357,496

11 Claims. (Cl. 148—9.5)

This invention relates to thermochemical metal scarfing, more particularly to method and apparatus for post-mixed preheat continuous wide oxygen stream desurfacing.

In such desurfacing, it has been necessary to provide three systems of gas supply. In addition to the main stream of oxidizing gas, the preheat flames to start and stabilize the reaction have required a large number of fuel gas jets, and a supply of preheat oxidizing gas to support combustion thereof. The development of post-mixed preheat flames to eliminate flashbacks has required a corresponding number of individual oxidizing gas streams, a separate stream for each fuel gas jet to support combustion thereof. The supply and distribution of these preheat oxidizing gas streams has been expensive as to first cost and maintenance.

It is therefore the main object of the present invention to eliminate the separate supply of preheat oxidizing gas. This we accomplish by utilizing the main stream of oxidizing gas as a source of supply of preheat oxygen for the fuel gas preheat flames.

It has also been desirable to bring the cutting stream of oxidizing gas and the upper preheat flames close to the zone of reaction, but prior expedients have resulted in damage to the orifices by scabs and slivers projecting from the work. It is therefore another object to space the orifices above the work to clear such scabs and slivers, while confining the stream of oxidizing gas and directing the preheat flames close to the zone of reaction. This we accomplish by increasing the angle of impingement to about 30° and extending the upper surface of the oxidizing gas slot beyond the lower surface thereof to bring the upper surface closer to the work than the lower surface thereof.

Heretofore the nozzle slot for the cutting stream of oxidizing gas has been manufactured as an insert, which was difficult and expensive to manufacture and replace. It is therefore another object to facilitate and economize the manufacture of this slot. This we accomplish by a built-in construction.

Another object is to provide a wide slot nozzle unit adapted to produce a flared stream, whereby a plurality of such units placed side by side for scarfing slabs, will have their flared streams merge to prevent a ridge therebetween.

Other objects and features of novelty will be apparent from the following description and the accompanying drawings, in which:

Fig. 1 is a vertical section through a desurfacing head according to, and for carrying out the method of, the present invention;

Fig. 2 is an exploded view of parts shown in Fig. 1;

Fig. 3 is a perspective view of the front and bottom of the nozzle blocks;

Fig. 4 is similar view of the rear of the nozzle blocks;

Fig. 5 is a section taken along the line 5—5 of Fig. 1;

Fig. 6 is a section taken along the line 6—6 of Fig. 1;

Fig. 7 is a section taken along the line 7—7 of Fig. 1;

2

Fig. 8 is a section through the preheat fuel gas ports; and

Fig. 9 is a plan of the water cooled skid plate.

Referring more particularly to the drawings, the desurfacing head comprises a nozzle base block 10, a skid block 12, an upper lip plate 14 and a lower lip plate 15. The nozzle base block 10 is bolted and gasketed to a manifold block 16, which comprises a selector valve assembly as disclosed in the Miller and Kolody Patent No. 2,524,920, issued October 10, 1950. The skid block 12 is bolted to the bottom of the base block 10. The lip plates 14 and 15 are bolted to the front face of the base block 10. This face is about 60° to the horizontal, so that the lip plates are at about 30°.

15 The lip plates 14 and 15 are spaced apart by end walls 18 to form the cutting slot 20 for the oxidizing gas. The upper lip plate 14 extends forwardly as at 21 about a third of its length beyond the lower lip plate 15, to confine the stream of oxidizing gas close to the reaction zone.

20 The end walls 18 are tapered outwardly at the forward portions of their inner sides as at 19, to cause the oxidizing gas stream to expand laterally and thereby provide good coverage when scarfing the four sides of a bloom or billet, or to prevent ridges between adjacent 25 units when placed side by side in a slab scarfing machine.

The opposed surfaces of the lip plates 14 and 15 are provided with uniformly laterally spaced corresponding grooves 22 extending from the rear forward for about two-thirds of the common extent of the lip plates. These 30 grooves 22 receive partitions 23, dividing the slot 20 into parallel oxidizing gas ways 24.

The oxidizing gas ways 24 register with the outlet ends of corresponding groups of bores 26 in the base block 10 and aligned with the central plane of the oxidizing

35 gas slot 20. These bores are supplied by a transverse bore 28, which, as shown in Fig. 5, receives a divider comprising a stem 31 provided with end walls 32 and discs 33 spaced corresponding to the slot partitions 23 and dividing the bore 28 into equal oxidizing gas chambers 35. Each chamber 35 is supplied by a bore 36 leading to corresponding passages 38 in the manifold block 16, and receiving oxidizing gas therefrom in the customary manner.

45 The upper lip plate 14 is provided with a row of closely spaced bores 40 for projecting jets of fuel gas down toward the reaction zone. These bores are supplied by a transverse bore 41 as best shown in Figs. 7 and 8. This bore 41 receives a divider comprising a stem 42 provided with end walls 43 and discs 44 spaced corresponding to the oxidizing gas partitions 23 and dividing the bore 41 into separate fuel gas chambers 45. The chambers 45 are each supplied by separate fuel gas bores 46 registering with corresponding bores 47 in the base block 10,

55 which in turn receive fuel gas from bores 48 registering with fuel gas supply bores 49 in the manifold block 16. For cooling the upper lip plate 14, a transverse bore 52 is provided, which receives cooling fluid from a longitudinal bore 54 shown in Fig. 6 in turn receiving from passages 56 registering with holes 58 in the slot end wall 18. From the bore 52 the cooling fluid passes through longitudinal bore 59 and registering bore 60 in the base block 10 which has a communicating bore 61 leading to the outlet bore 62 in the manifold block 16.

65 The lower lip block 15 is provided with a row of closely spaced bores 64 for preheat gas, similar to the bores 40 in the upper block. These are fed by a transverse bore 65, provided with an identical divider 42 which divides the bore 65 into chambers in the same way as shown in Figures 7 and 8 for the lower block. The chambers formed thereby are fed by longitudinal bores 67 register-

ing with bores 68 in the base block 10 communicating with the supply bores 48 from the manifold passage 49.

For cooling the lower lip block 15, a transverse bore 72 is provided, which receives cooling fluid from a longitudinal bore 73 supplied by a vertical bore 74. From the transverse bore 72, the cooling fluid passes out through longitudinal bore 75 and passages 76 to the holes 58 in the end wall 18.

The skid block 12 contains a cooling jacket 80 which receives cooling fluid from the supply passage 81 in the manifold block 16, and registering vertical passage 82 in the base block 10, joining a transverse passage 83 leading to a vertical passage 84, which registers with the skid block entrance passage 85. The cooling jacket 80 by means of a passage 87 is in parallel relation to a bore 86 in the front of the skid block and having out passage 88. Furthermore, the cooling fluid passes to outlet 89 which is in register with the lower lip plate inlet 74.

We claim:

1. In a process for thermochemically scarfing metal bodies, discharging a sheet-like stream of oxidizing gas onto a reaction zone extending across the entire transverse extent of the surface of a metal body and at an acute angle of impingement to the work surface of said metal body, confining said sheet-like stream of oxidizing gas between upper and lower spaced apart surfaces laterally continuous for the entire transverse extent of the surface of said body, discharging a row of jets of preheat fuel gas at an acute angle to said oxidizing gas stream onto said reaction zone from a row of orifices ahead of at least one of said surfaces, and supplying preheat oxidizing gas from said sheet-like stream of oxidizing gas to support combustion of said jets of fuel gas and produce post-mixed preheat flames therefrom.

2. In a process for thermochemically scarfing metal bodies, discharging a sheet-like stream of oxidizing gas onto a reaction zone extending across the entire width of a metal body and at an acute dihedral angle of impingement to the work surface of said metal body, confining said sheet-like stream of oxidizing gas between upper and lower spaced apart surfaces laterally continuous for the entire width of said body, discharging a row of jets of preheat fuel gas at an acute angle to said oxidizing gas stream onto said reaction zone from a row of orifices below said lower surface, and supplying preheat oxidizing gas from said sheet-like stream of oxidizing gas to support combustion of said jets of fuel gas and produce post-mixed preheat flames therefrom.

3. In a process for thermochemically scarfing metal bodies, discharging a sheet-like stream of oxidizing gas onto a reaction zone extending across the entire width of a metal body and at an acute dihedral angle of impingement to the work surface of said metal body, confining said sheet-like stream of oxidizing gas between upper and lower uniformly spaced apart surfaces laterally continuous for the entire width of said body, discharging a row of jets of preheat fuel gas at an acute angle to said oxidizing gas stream onto said reaction zone from a row of orifices above said upper surface and impinging said stream of oxidizing gas a substantial distance ahead of the said lower surface and supplying preheat oxidizing gas from said sheet-like stream of oxidizing gas to support combustion of said jets of fuel gas and produce post-mixed preheat flames therefrom.

4. In a process for thermochemically scarfing metal bodies, discharging a sheet-like stream of oxidizing gas onto a reaction zone extending across the entire width of a metal body and at an acute dihedral angle of impingement to the work surface of said metal body, confining said sheet-like stream of oxidizing gas between upper and lower uniformly spaced-apart surfaces laterally continuous for the entire width of said body, said upper surface extending smoothly and continuously forwardly beyond said lower surface along said inclined ox-

idizing gas stream in overhanging relation to said lower surface for a length measured along said stream greater than the spacing of said surfaces toward the reaction zone to terminate the confinement of the top of said oxidizing gas stream closer to the reaction zone than the termination of confinement of the bottom thereof, and thereby discharge the stream of oxidizing gas directly onto the reaction zone of the work surface, discharging a transversely distributed flow of preheat fuel gas at an acute dihedral angle to said oxidizing gas stream from transversely arranged orifice means ahead of the termination of confinement of at least one of said oxidizing gas stream confining surfaces, and supplying preheat oxidizing gas from said sheet-like stream of oxidizing gas to support combustion of said fuel gas to produce a transversely distributed post-mixed preheat flame.

5. In apparatus for thermochemically scarfing metal bodies, a desurfacing head comprising a nozzle block, a skid plate secured to said nozzle block and having a work engaging surface, said nozzle block having a front seating surface at an angle of about 60° to said work engaging surface, upper and lower lip plates having their rear ends abutting and secured to said seating surface of said nozzle block in spaced apart relation, side walls closing the space between said lip plates and forming a cutting oxygen slot, transversely arranged preheat fuel gas orifice means in the front face of at least one of said lip plates, said one of said lip plates being free of any internal oxygen passages, the preheat oxygen for said fuel gas orifice means being supplied by said cutting oxygen slot to form transversely distributed post-mixed preheat flame.

6. In apparatus for thermochemically scarfing metal bodies, a desurfacing head comprising a nozzle block, a skid plate secured to said nozzle block and having a work engaging surface, said nozzle block having a front seating surface at an angle of about 60° to said work engaging surface, upper and lower lip plates having their rear ends abutting and secured to said seating surface of said nozzle block in spaced apart relation, said upper lip plate extending integrally forwardly about a third of its length beyond said lower lip plate to bring the front bottom edge of said upper lip plate below the front top edge of said lower lip plate, side walls closing the space between said lip plates and forming a cutting oxygen slot, and means in said nozzle block including orifice means in said front seating surface for supplying cutting oxygen to said slot.

7. In apparatus for thermochemically scarfing metal bodies, a desurfacing head comprising a nozzle block, a skid plate secured to said nozzle block and having a work engaging surface, said nozzle block having a plane front surface at an angle of about 60° to said work engaging surface, upper and lower lip plates having their rear ends abutting and secured to said plane front surface of said nozzle block in spaced apart relation, said upper lip plate extending integrally forwardly about a third of its length beyond said lower lip plate to bring the front bottom edge of said upper lip plate below the front top edge of said lower lip plate, side walls closing the space between said lip plates and forming a cutting oxygen slot, means in said nozzle block for supplying cutting oxygen to said slot, transversely arranged preheat fuel gas orifice means in the front face of at least one of said lip plates, fuel gas passage means in said one of said lip plates leading to said orifice means and corresponding fuel gas passage means in said nozzle block leading to registering aperture means in the abutting surface thereof for supplying fuel gas to said orifice means.

8. In apparatus for thermochemically scarfing metal bodies, a desurfacing head comprising a nozzle block, a skid plate secured to said nozzle block having a work engaging surface, said nozzle block having a front seating surface at an angle of about 60° to said work engag-

ing surface, upper and lower lip plates having their rear ends abutting and secured to said seating surface of said nozzle block in spaced apart relation, side walls closing the space between said lip plates and forming a cutting oxygen slot, the inner surfaces of said lip plates having longitudinal grooves, vertical partitions fitted into said grooves and dividing said slot into cutting oxygen ways, said nozzle block having passage therein for supplying cutting oxygen to said ways.

9. In apparatus for thermochemically scarfing metal bodies, a desurfacing head comprising a nozzle block, upper and lower lip plates secured in the front of said nozzle block in spaced apart relation, both of said lip plates extending forward from said nozzle block for a length many times the distance therebetween, and the front edge of said upper lip plate overhanging that of said lower lip plate for a length greater than the distance therebetween, side walls closing the space between said lip plates and forming a cutting oxygen slot, means in said nozzle block for supplying oxidizing gas to said slot, a row of preheat orifices in the front of at least one of said lip plates, fuel gas passages in said lip plate leading to said row of preheat orifices, corresponding fuel gas passages in said nozzle block leading to registering apertures of said lip plate to form continuous conduits for supplying fuel gas to said row of preheat orifices, said lip plate having a transverse bore near its front end, said row of preheat orifices communicating with said bore, and a distributor inserted in said bore and having uniformly spaced annular seals dividing said ports into equal groups.

10. In a desurfacing head for thermochemical metal removal, a nozzle block, upper and lower lip plates secured to said nozzle block in spaced apart relation, both of said lip plates extending forward from said nozzle block for a length many times the distance therebetween, and the front edge of said upper lip plate overhanging that of said lower lip plate for a length greater than the distance therebetween, side walls closing the space between said lip plates and forming with the inner surface

- of said lip plates a cutting oxygen slot, the inner surfaces of said lip plates having longitudinal grooves, vertical partitions fitted into said grooves and dividing said slot into cutting oxygen ways, said nozzle block having passages therein for supplying cutting oxygen to said ways, at least one of said lip plates having a transverse bore near its front end, a row of preheat ports in the front of said plate communicating with said bore, and a distributor inserted in said bore and having uniformly spaced annular seals dividing said ports into equal groups.
11. In a desurfacing head for thermochemical metal removal, a nozzle block, upper and lower lip plates secured to the front of said nozzle block in spaced-apart relation, both of said lip plates extending forward from said nozzle block for a length many times the distance therebetween, and the front edge of said upper lip plate overhanging that of said lower lip plate for a length greater than the distance therebetween, side walls closing the space between said lip plates and forming a cutting oxygen slot, said nozzle block having a transverse bore receiving a supply of cutting oxygen, a distributor in said bore having annular seals dividing said bore into chambers, and longitudinal bores in said nozzle block communicating with said chambers and opening into the front face of said nozzle block between said lip plates, for supplying cutting oxygen to said slot.
